United States Patent Office

Des. 214,860
Patented Aug. 5, 1969

214,860

SIGN

Enrique Avila, % Central De Malta, S.A., Paseo De La
Reforma 144, 5th Floor, Mexico City, Mexico 6

Filed July 9, 1968, Ser. No. 12,664

Term of patent 14 years

Int. Cl. D20—03

U.S. Cl. D96—12

Fig. 2

Fig. 3

Fig. 1

FIG. 1 is a plan view of a sign showing my new design;

FIG. 2 is a top plan view; and

FIG. 3 is a side elevational view thereof.

The opposite side of the design is a mirror image of FIG. 1.

I claim:

The ornamental design for a sign, as shown and described.
